US00D768978S

(12) **United States Design Patent** (10) **Patent No.:** **US D768,978 S**
Ma (45) **Date of Patent:** **** Oct. 18, 2016**

(54) **UMBRELLA BASE**

(71) Applicant: **Oliver Joen-an Ma**, Arcadia, CA (US)

(72) Inventor: **Oliver Joen-an Ma**, Arcadia, CA (US)

(**) Term: **14 Years**

(21) Appl. No.: **29/522,207**

(22) Filed: **Mar. 27, 2015**

(51) LOC (10) Cl. **03-03**

(52) U.S. Cl.

USPC **D3/10**

(58) **Field of Classification Search**

USPC D3/5, 6, 10, 11, 12, 14, 16; D6/708, D6/708.2, 708.24; D8/354

CPC A45B 23/00; A45B 11/00; A45B 223/0025; B65D 2519/00323; B65D 2519/00029;

(57) **CLAIM**

The ornamental design for an umbrella base, as shown and described.

DESCRIPTION

FIG. 1 is a perspective view of an umbrella base showing my new design;

FIG. 2 is a front view of the design of FIG. 1;

FIG. 3 is a rear view of the design of FIG. 1;

FIG. 4 is a left side view of the design of FIG. 1;

FIG. 5 is a right side view of the design of FIG. 1;

FIG. 6 is a top view of the design of FIG. 1; and,

FIG. 7 is a bottom view of the design of FIG. 1.

The broken lines depict portions of the article that form no part of the claimed design.

1 Claim, 7 Drawing Sheets

US D768,978 S
